UNITED STATES PATENT OFFICE

162,364

JEWELRY BOX

Milton Weill, New York, N. Y.

Application June 8, 1950, Serial No. 10,404

Term of patent 7 years

(Cl. D86—9)

To all whom it may concern:

Be it known that I, Milton Weill, a citizen of the United States, and a resident of the city, county, and State of New York, have invented a new, original, and ornamental Design for a Jewelry Box, of which the following is a specification, reference being had to the accompanying drawing, forming part thereof.

Fig. 1 is a top plan view of a jewelry box, showing my new design;

Fig. 2 is a front elevational view thereof; and
Fig. 3 is a side elevational view thereof.

I claim:

The ornamental design for a jewelry box, as shown.

MILTON WEILL.
